UNITED STATES PATENT OFFICE.

FREDERICK C. HODSHON, OF BUFFALO, NEW YORK.

SET BOARD FOR HATS.

1,258,219.

Specification of Letters Patent. Patented Mar. 5, 1918.

Application filed January 26, 1916. Serial No. 74,339.

To all whom it may concern:

Be it known that I, FREDERICK C. HODSHON, a citizen of the United States of America, and a resident of the city of Buffalo, county of Erie, and State of New York, have invented certain new and useful Improvements in Set-Boards for Hats, of which the following is a full, clear, and exact description.

10 It is well known to those skilled in the art that it is very often necessary to change the shape of a stiff or Derby hat. This is sometimes accomplished by stretching the hat with a hat block, but the only successful 15 way of changing the contour is by first softening the shellac or other stiffening material in the brim of the hat by the application of heat.

The general object of my invention has 20 been to provide a set board which is heated by electricity and upon which the hat may be placed and the stiffening in the brim thereof easily and quickly heated and softened.

25 Another object has been to provide a device of this character which shall be extremely simple, cheap to manufacture, and, at the same time, easy to operate and absolutely fire proof.

30 The above objects and advantages have been accomplished by the device shown in the accompanying drawings, in which:

Figure 1 is a transverse, sectional elevation taken on line 1—1 of Fig. 2.

35 Fig. 2 is a fragmentary, sectional, plan view of the same with the top part of the insulation broken away, showing the resistance wire exposed.

Fig. 3 is a reduced side elevation of my 40 device.

My device comprises a base 5, which may be of any suitable shape, but it is preferably formed with an upwardly extending side wall 6, and a lower beaded edge 7 to give 45 it sufficient rigidity. The base member 5 is preferably elliptical in its contour.

The walls are preferably provided with a plurality of apertures 8, whereby suitable ventilation is had so that the heat within 50 the walls may be carried off.

On top of the base member 5 is disposed a thick pad 9 of refractory material, preferably asbestos. Embedded in this block and near its upper surface is the heating member 10 of my device. This member comprises a resistance wire made of platinum,

German silver, iron or any other suitable material and of a size adapted to the electric current used. In practice, I form the block 9 of a thick sheet of asbestos, then 60 place the resistance wire, forming the member 10, thereon and secure it to the block by any suitable means. I then place on top of the heating member two or three thin sheets of asbestos. 65

The resistance wire of the heating member 10 is arranged in a flat spiral and has its inner end starting at some distance from the center of the device, thus leaving a clear elliptical space at the center where heat is 70 not needed. The spiral starts at a point where it will be beneath the brim of the hat and is coiled around in any desired number of turns until it reaches a point near the outer edge. The terminals of this 75 heating member are attached to suitable leads 15 which are extended down through the asbestos block 9 and are attached to a suitable electric connector 11. This connector is of any desired type, but preferably 80 one which can be attached to a source of electric power by means of a flexible electric cord.

On top of the pad 9 is arranged a plate 12, upon which the hat is placed. This plate 85 is made of thin sheet metal, preferably of copper, although any other suitable material may be used, if desired. Beneath the block 9 is arranged a sheet of thin material 13, which protects the block from injury. 90 The whole is bound together by means of a plurality of bolts 14, which pass through the upper plate 12, the asbestos block 9 and also plate 13, thereby securing these parts to the upper edge of the base member 5. 95

When the device is to be used, a suitable source of electric current is connected to the connector 11 in the well known way, whereupon the temperature of the resistance wire will be raised and thus heat the plate 100 12. The hat is now placed upon this plate and heated until the shellac in the brim is softened, whereupon it may be shaped as desired.

Having thus described my invention, what 105 I claim is:

A set board for hats comprising a base, a bottom sheet of thin material located on the base, a thick pad of refractory material mounted on the sheet, a heating member, 110 embedded in the pad, comprising a resistance wire arranged in a flat spiral, leaving

a central space and coiled around in any desired number of turns, an electrical connection, leads extending from the connector to the terminals of the heating member, an upper plate located on the top of the pad, and means securing the bottom sheet, pad, and upper plate together and to the base.

In testimony whereof, I have hereunto signed my name in the presence of two subscribing witnesses:

FREDERICK C. HODSHON.

Witnesses:

J. WM. ELLIS,

WALTER H. KELLEY.
